N. MADSEN

DRILLING APPARATUS

Filed Feb. 4, 1925

Inventor:
Norman Madsen
by, *Tracey*

Attorney.

UNITED STATES PATENT OFFICE.

NORMAN MADSEN, OF MICHIGAN CITY, INDIANA, ASSIGNOR TO SULLIVAN MACHINERY COMPANY, A CORPORATION OF MASSACHUSETTS.

DRILLING APPARATUS.

Application filed February 4, 1925. Serial No. 6,908.

My invention relates to drilling apparatus and more particularly to drilling apparatus of the oil well type.

An object of my invention is to provide an improved drilling apparatus. Another object of my invention is to provide improved raising and lowering means for the drill rods of such an apparatus. Still another object of my invention is to provide an improved lifting bail or elevator for raising and lowering drill rods which is of an exceedingly simple and rugged structure and which may be adjusted with facility. These and other objects and advantages of my invention will, however, hereinafter more fully appear.

In the accompanying drawings I have shown, for purposes of illustration, one form which my invention may assume in practice.

20 In these drawings,—

Fig. 1 is an elevational view, partially broken away in section, of my improved lifting bail disposed in operative position relative to the drill rods.

25 Fig. 2 is a transverse horizontal sectional view taken substantially on line 2—2 of Fig. 1.

Fig. 3 is a detail perspective view of a portion of my improved lifting bail illustrating 30 the improved lifting clevis and gate lock, the latter being shown in its open or released position.

Fig. 4 is a detail elevational view partially in section of the lifting bail, the gate lock being illustrated in its raised position.

In this illustrative form of my invention I have shown a lifting bail or elevator of improved form, generally designated 1, which comprises a body portion or rod clevis 2 having radially spaced vertical bores 3 within which the ends 4 of a bail 5 are suitably secured. The body portion 2 is provided with an enlarged central opening 6 open at one side and adapted to embrace the usual drill rods 7 and is further provided at its upper surface with a horizontal plane raised portion or boss 8 adapted to engage the bottom surface of a usual enlarged collar or coupling 9 suitably secured to the drill rod 7. The bail 5 is adapted to be engaged by a hook and cable connection, not shown, which cable passes upwardly around a pulley or sheave carried by the well derrick and then downwardly

to the usual hoisting drum of the drilling mechanism in a well known manner.

It will herein be noted that in my improved construction the casing 2 is provided with a lateral lug 10 having a vertically disposed stepped bore 11 within which a pin or bolt 12 is slidably disposed. The bolt 12 is secured at its opposite ends as by an enlarged head as 13 and a riveted portion 14, within vertically spaced lateral ears or lugs 15 formed on a pivoted member or gate lock 16 which is adapted to close the open side of the opening 6. A coiled spring 17 is disposed in the bore 11 and is adapted to react upon a shoulder 18 formed on the bolt 12 and the upper end of the bore normally tending to hold the member 16 in its lowermost or locked position. The gate member 16 is provided with a concave inner surface 19 adapted to engage the periphery of the drill rods 7 and is further provided with a lug or latch member 20 adapted to register with a recess 21 formed within the casing 2. As illustrated, a suitable clearance 22 is provided between the bottom surface of the lug 10 and the lower ear 15 of the member 16 to permit free vertical movement of the latter.

In the use of my improved lifting bail it will herein be noted that when it is desired to raise the drill rods from the well, the gate lock 16 is grasped by the operator and is raised upwardly, as shown in Fig. 4, compressing the spring 17 and releasing the lug or latch 20 from the recess 21 in the casing 2, thus permitting the gate 16 to be swung outwardly about the pin 12 as a pivot to substantially the position shown in Fig. 3. The casing or rod clevis 2 of the lifting bail is then placed about the drill rod below the collar or coupling 9 and the gate 16 is then swung inwardly and when in the position shown in Fig. 2 the lug 20 snaps back within the recess 21 by means of the spring 17 rigidly locking the casing and gate in operative position. The usual hook and cable is then suitably connected to the lifting bail 5 and the rods 7 raised from the well in any suitable manner.

From the foregoing description it will herein be observed that the improved lifting bail is provided which is of an exceedingly simple and rugged character especially adapted to use in oil well drilling wherein

the bail may be readily attached to or released from the drill rods with a minimum of effort and time.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

15. 1. In a lifting bail for drill rods, a rod clevis having lugs for receiving the bail and a central laterally extending opening, a lateral lug formed on said clevis and having a vertical bore, a pivot pin slidably mounted in said bore, a gate member for closing the open side of said clevis, said gate member being connected to said pin, and a spring in said bore acting on said pin for maintaining said gate member in its closed position.
20. 2. In a lifting bail for drill rods, a rod clevis having lugs for receiving the bail and a central laterally extending opening, said clevis having a recess, a lateral lug formed on said clevis and having a vertical bore, a pivot pin slidably mounted in said bore, a gate member for closing the open side of said clevis, said gate member being connected to said pin and having a locking lug 25 adapted to cooperate with said recess, and a spring in said bore acting on said pin for maintaining said gate member in its closed position with said locking lug disposed in said recess.
30. 3. In a lifting bail for drill rods, a rod clevis having openings for receiving the bail and a central laterally extending opening

for receiving the drill rods, a lateral lug formed on said clevis and having a vertical bore, a pin slidably mounted in and extending through said bore, a gate member having vertically spaced lateral lugs connected to the opposite ends of said pin, said gate member being adapted to close the open side of said clevis, and a spring disposed in said bore and acting on said pin for maintaining said gate member with the upper surface of the lug formed thereon in engagement with the lug on said clevis, said spring permitting movement of the lower lug on said gate member into engagement with the lower surface of the lug on said clevis.

4. In a lifting bail for drill rods, a rod clevis having openings for receiving the bail and a central laterally extending opening for receiving the drill rods, a lateral lug formed on said clevis and having a vertical bore, a pin slidably mounted in and extending through said bore, a gate member having vertically spaced lateral lugs connected to the opposite ends of said pin, said gate member being adapted to close the open side of said clevis, a spring disposed in said bore and acting on said pin for maintaining said gate member with the lug formed thereon in engagement with the upper surface of the lug on said clevis, said spring permitting movement of the lower lug on said gate member into engagement with the lower surface of the lug on said clevis, and means for locking said gate member to said clevis including cooperating elements carried respectively by said gate member and said clevis, the vertical movement of said gate member releasing the locking engagement of said elements.

In testimony whereof I affix my signature.

NORMAN MADSEN.
